United States Patent Office.

ALEXANDER GRILLET, OF PHILADELPHIA, PENNSYLVANIA.

Letters Patent No. 105,798, dated July 26, 1870.

IMPROVED BEDSTEAD-FASTENING.

The Schedule referred to in these Letters Patent and making part of the same.

I, ALEXANDER GRILLET, of Philadelphia, county of Philadelphia, State of Pennsylvania, have invented an Improved Bedstead-Fastening, of which the following is a specification.

Nature and Object of the Invention.

My invention relates to a cheap and simple bedstead-fastening, consisting of a loose metal pin, adapted partly to an upwardly-inclined recess in the bedstead-rail, and partly to a downwardly-inclined recess in the post.

My invention also consists in making the said plates with ribs and recesses, arranged, in the peculiar manner described hereafter, in respect to the orifices for receiving the inclined pin, so that, while the rib of one plate will fit the recess of the other, both plates may be alike, and may be cast from the same pattern.

Description of the Accompanying Drawing.

Figures 1 and 2 represent the perspective views of the plates used as part of my improved bedstead-fastening;

Figure 3, a sectional view of the fastening, complete;

Figure 4, the same, showing the parts detached from each other; and

Figures 5, 6, and 7, views of modifications.

General Description.

A represents part of the post, and
B part of the rail of a bedstead.

Into the end of the rail is let, and there secured, a metal plate, D, having at the rear a projection, a, to permit the formation in front of an upwardly-inclined orifice, b, for the reception of one-half of the inclined pin E. A similar plate, D', is let into and secured to the post a, but in a position the reverse of the plate D, so that its orifice, b', may be inclined downward for receiving the other half of the inclined pin E.

The plate D, in the rail, has in front a rib, d, extending from the upper edge of the said plate to its orifice, b, and adapted to the recess e, in the plate D' of the post. In like manner the latter plate has a rib, d', adapted to a recess, e', in the plate D.

When the rail, with its plate, is fitted to the plate of the post, with the inclined pin projecting half way into each plate, as shown in fig. 3, all lateral twisting of the rail is prevented by the ribs of one plate fitting into the recesses of the other, while the

position of the pin E is such that the greater the pressure applied to the top of the rail, the more securely will the latter be bound to the post.

It will be observed, on reference to figs. 1 and 2, that the plates D and D' are precisely alike, and may be cast from the same pattern, all that is necessary in applying them being to arrange that for the rail in a position the reverse of that for the post, as shown.

In fig. 5 the plates are shown as reduced in size and slightly modified in form, and an advantageous method of securing the plates to the post and rail, by means of screws x x, is also represented.

Another modification of the invention is shown in fig. 6, the plates in this case taking the form of tubes, which are inserted, in an inclined position, into the post and rail, the outer end of each plate being cut away so as to form a rib and recess, adapted to a corresponding rib and recess of the opposite plate. In some cases, also, where the rail and post are of hard wood, the metal plates may be altogether dispensed with, and a loose inclined metal pin be adapted, partly to the post and partly to the rail, as shown in fig. 7.

The steadyng-lugs y y, illustrated in connection with the independent pin in fig. 7, may be either used or not, as desired.

Inclined pins, secured permanently to the rail or post, are objectionable, as they are apt to become bent or broken during the transportation or storage of the parts of the bedstead, the latter being thereby rendered unserviceable. It will be apparent that my improvement obviates this difficulty, as the pins are removed when the bedstead is taken apart.

Claims.

1. A rail, having at the end an inclined socket, and a post, having an inclined socket at one side of the same, in combination with a loose pin or bar, E, adapted to the sockets in the post and rail, substantially as described.

2. The plates D and D', having ribs and recesses, arranged, in respect to the orifices, for receiving the inclined detachable pin, as set forth.

In testimony whereof I have signed my name to this specification in the presence of two subscribing witnesses.

ALEX. GRILLET.
